UNITED STATES PATENT OFFICE.

FRANK R. SINNING, OF RAMSEY, ILLINOIS. ASSIGNOR TO FREDERICK HACHMANN,
OF CHICAGO, ILLINOIS.

COMBINATION RAIL LINER, TIE SPACER, AND RAIL-JOINT ELEVATOR.

Application filed January 5, 1923. Serial No. 610,771.

This invention relates to a combination rail liner, tie spacer and rail joint elevator, and particularly to an implement of such construction that it may be effectively employed to properly position railroad rails and ties to assure the smooth operation of railway vehicles thereover.

It is an important object of the present invention to provide an implement of the class described which will effect a proper positioning of the rails and ties with a minimum of effort on the part of the operator.

It is another object of this invention to provide a combination implement of the class described which is of relatively light weight and which may be economically manufactured.

It is an important object of this invention to provide a single implement adapted for use for a variety of purposes.

Other and further important objects of this invention will be apparent from the disclosures in the specification and the accompanying drawings.

The invention (in a preferred form) is illustrated on the drawings and hereinafter more fully described.

On the drawings:

Figure 1 is a front elevation of an implement embodying the principles of this invention.

Figure 2 is a side elevation thereof.

Figure 3 is a top plan view thereof.

Figure 4 is a central vertical section, with parts in elevation, taken through an implement embodying the principles of the present invention.

Figure 5 is a side elevation, with parts in section, illustrating one application of the implement of this invention.

Figure 6 is a view similar to Figure 5, illustrating another application.

Figure 7 is a side elevation illustrating the implement positioned between railroad ties to elevate a rail joint.

Figure 8 is a side elevation illustrating the implement positioned between railroad ties to effect a proper spacing thereof.

As shown on the drawings:

The implement of this invention comprises a base 1 which has integral forwardly extending portions 2 on either side thereof, said portions 2 having downwardly extend-

ing integral flanges 3 along their outer edges. Extending upwardly from the base 1 and outwardly over the extensions 2 are spaced integral brackets 4 which are connected at their forward ends by an integral plate 5 extending upwardly from the base 1 between said brackets. In order that the base 1 may be retained in firm association with the surface on which it is being used, the same is provided with a plurality of anchoring means. Said anchoring means comprise a rearwardly concave wedge-shaped member 6 which is integral with the base 1 and extends downwardly therefrom, and a plurality of spike members 7 which extend downwardly from the forward end 70 of the base and from the extensions 2.

Pivotedly mounted on a pin 8 removably engaged through registering apertures formed in the brackets 4 near the upper ends thereof is an operating lever 9 which is recessed at 10 to receive an ordinary lining bar 10^a or similar device which may be grasped by an operator to rotate the lever about its pivot point. For purposes of convenience, the pin 8 is removable and is secured in position relative to the brackets 4 by a usual cotter pin 11.

The operating lever 9 has depressions 12 and 13 formed in the face thereof, the depression 12 affording means for engagement with the flange of a rail 14 in the manner indicated in Figure 5 and the depression 13 allowing clearance for the ball of the rail. Pivoted on a pin 15 which is removably engaged in registering apertures in the outer ends of the extensions 2 is a rail engaging member 16 which has a flange or hook portion 17 formed on its outer end and which is provided with two lateral extensions 18 extending outwardly from its face, between said flange and the pin 15. The rail engaging member 16 is adapted to be engaged in the depression 12 for operation by the operating member 9, an extension ridge 19 formed on the face of said lever 9 acting to assure proper engagement between these parts.

Figure 6 illustrates the use of the rail engaging member 16 showing the face thereof being held in engagement with the flange of the rail 14 by means of the hook member 17 thereon, and from the illustration in Figure 8 it will be apparent that

with the parts in the position shown, when the operating lever 9 is rotated about its pivot point, a lateral thrust will be imparted to the rail 14 to properly align the 5 same without lifting the rail from the tie.

The implement of this invention is also adapted to be used in the manner indicated in Figure 7 for elevating sunken rail joints 20 and retaining the same in elevated position until sufficient material is tamped under 10 the ties to assure permanent positioning of the rail joint at the proper elevation. In using the device for this purpose, the under side of the rail 14 is engaged by the face 15 of the lever 9 below the depression 12 and by rotating said lever about its pivot point the joint 20 may be raised to the proper elevation. The joint is retained in this raised position until the tamping is completed 20 by means of a notched locking member 21 which is pivotally secured on the side of the lever 9 at 22 and which has angle notches 23 therein that are adapted to be removably engaged over a pin 24 projecting 25 outwardly from the side of one of the brackets 4. The pivot point at 22 is afforded by a pin which extends outwardly from a boss 22^a integrally formed on the side of the lever 9, and said boss 22^a is adapted 30 to set in a depression 22^b formed in the upper face of one of the brackets 4 in the manner indicated in Figure 2.

The device may also be used in the manner shown in Figure 8 for repositioning ties 35 25 which have moved into improper position due to creeping, and in this use of the device the same is inserted between the ties, the anchoring means 7 engaging the face of one of the ties and the face of the operating lever 9 engaging the face of the other tie. The rotation of the lever 9 about its pivot point acts to effect a separation of the ties and a movement thereof into proper relative position.

45 It will be apparent from the foregoing description that this invention provides an implement which may be conveniently used either in the manner shown in Figure 5, or in the manner shown in Figure 6, for lining railroad rails, and which may be used in the manner shown in Figure 7 for elevating rail joints or in the manner shown in Figure 8 for properly repositioning railroad ties.

The device is relatively light in weight 55 and is of simple and rugged construction, and may be consequently economically manufactured and conveniently operated.

I am aware that numerous details of construction may be varied through a wide 60 range without departing from the principles of this invention, and I therefore do not

purpose limiting the patent granted otherwise than necessitated by the prior art.

I claim as my invention:

1. A device of the kind described comprising a base, supporting means extending upwardly therefrom, an operating lever pivoted on the supporting means and having depressions in its face conforming to the contour of a rail to be engaged thereby, 70 and rail engaging means pivoted on the base and adapted to be operated by the lever.

2. A device of the kind described comprising a base, supporting means extending upwardly therefrom, an operating lever 75 pivoted on the supporting means, a second lever pivoted on the base adapted to engage with the operating lever on its lower side when elevated and to clear the lower end of said operating lever when lying flat against 80 said base.

3. A device of the kind described comprising a base, supporting means extending upwardly therefrom, an operating lever pivoted on the supporting means and having 85 a clearance depression in its face conforming to the contour of a rail, and a rail engaging means pivoted on the base having an upper surface adapted to engage a rail and a lower surface adapted to be engaged by 90 said operating lever when in elevated position.

4. A device of the class described comprising a base, supporting means extending upwardly therefrom, an operating lever 95 pivotally mounted in said supporting means, and an auxiliary rail engaging member adapted to lie under said rail when said lever engages said rail but adapted to be conjointly used with said lever when said rail is at a predetermined distance from the fulcrum of said lever.

5. A device of the class described comprising a base, a pair of members pivotally mounted thereon, one of said members 105 adapted to engage a rail directly and the other of said members adapted to be used conjointly with said first member when said rail is at a predetermined distance from the fulcrum of said lever.

6. A device of the class described comprising a base, a pair of members pivotally mounted thereon one in advance of the other, the rearwardly pivoted member being adapted 110 to engage and move a rail through a certain distance and then to act conjointly with said forwardly pivoted member to cause said latter member to engage the rail to advance the same through a greater distance.

In testimony whereof I have hereunto subscribed my name.

FRANK R. SINNING,
